(57) **CLAIM**

The ornamental design for a display screen or portion thereof with graphical user interface, as shown and described.

DESCRIPTION

FIG. 1 is a front view of a display screen or portion thereof with graphical user interface showing our new design; and, FIG. 2 is another front view of the display screen or portion thereof with graphical user interface showing our new design.

The long-dash/short-dash/short-dash broken lines in FIGS. 1 and 2 illustrate a display screen and form no part of the claimed design. The even broken lines illustrate portions of the graphical user interface and form no part of the claimed design.

FIG. 2 is identical to FIG. 1 except that FIG. 2 does not show the even broken lines that are shown in FIG. 1 and form no part of the claimed design.
